Edw. J. Thole INVENTOR
BY Victor J. Evans

WITNESS:

UNITED STATES PATENT OFFICE.

EDWARD J. THOLE, OF EVANSVILLE, INDIANA.

BOX.

1,424,127.

Specification of Letters Patent. Patented July 25, 1922.

Application filed September 28, 1920. Serial No. 413,315.

To all whom it may concern:

Be it known that I, EDWARD J. THOLE, a citizen of the United States, residing at Evansville, in the county of Vanderburg and State of Indiana, have invented new and useful Improvements in Boxes, of which the following is a specification.

This invention relates to boxes designed primarily for the packing of cereals and the like and has for its object the provision of a box which may be formed of card-board or the like, having in one end a discharge opening normally closed by a sliding plate, the plate being initially sealed in closed position by a gummed label or sticker.

An important object is the provision of a device of this character which will be a great advantage when used for packing cereals and the like inasmuch as it obviates the necessity for cutting or tearing open the package to remove the contents and thus maintains the contents in far better condition as the sliding plate is intended to be closed after the desired amount of the contents has been removed.

An additional object is the provision of a box of this character which will be simple and inexpensive in manufacture, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a perspective view of one end of a box constructed in accordance with my invention and showing it in its initial position,

Figure 2 is a plan view of the end showing the sliding plate in open position,

Figure 3 is a cross sectional view on the line 3—3 of Figure 2, and

Figure 4 is a cross sectional view on the line 4—4 of Figure 2.

Referring more particularly to the drawings, the numeral 10 designates a box which may be formed of any suitable material, in ordinary practice preferably of card-board. One end 11 of the box is formed with a rectangular cut away portion 12 extending entirely to one edge. Disposed against the

underside of this end 11 is a sheet or card-board or the like 13 which is preferably glued or pasted in place and which is of substantially U-shape to provide a bight portion 14 which extends across approximately one half of the opening 12 and to provide arms 15 which extend along the sides of the opening 12. If necessary, spacing strips 16 may be secured between this sheet and the end 11 so that there will be a guide space 17 between the sheet 13 and the end 11.

The numeral 18 designates the cover which is formed as a sheet or plate of card-board or the like and which has its side edges engaged within the guides 17. This sheet 18 is slidable between the strips 15 and the end 11 so that it may cover or uncover that portion of the opening 12 which is not covered by the sheet 14. At one edge the sheet 18 is formed with a tab 19 adapted to be bent up to serve as a handle.

Under ordinary conditions, that is when the box is packed ready for shipment, the sheet 18 is in closed position with the tab 19 lying flat upon the sheet portion 14. The cover 18 is held in this closed position by means of a suitable sticker or label 20. When the purchaser wishes to use the box he tears off the sticker 20, presses the tab 19 upwardly to serve as a handle and then slides the cover 18 into non-obstructing relation to the opening whereupon the contents of the package may be easily poured out. It is then intended that the cover 18 be returned to normal position covering the opening so as to exclude dirt, moisture, and the like.

From the foregoing description and a study of the drawings it will be apparent that I have thus provided a very simply constructed and consequently inexpensive box of the character and for the purpose specified, which will be not only very convenient and a great labor saver but also that it will be very sanitary in use.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim;

A box provided in one end with an opening, a U-shaped member secured at said opening at the inner side of the end and including a bight portion partly covering the opening and further arms extending along the sides of the opening, spacing strips secured between said ends and said U-shaped

member whereby to space said arms away from the inner sides of the ends, and a plate 10
slidable between said ends and the U-shaped member and provided with a tab serving to form a handle.

In testimony whereof I affix my signature.
EDWARD J. THOLE.
